UNITED STATES PATENT OFFICE.

JOHN F. HAMILTON, OF SOUTH FRAMINGHAM, MASSACHUSETTS.

GUIDE FOR STRAW-BRAID-SEWING MACHINES.

SPECIFICATION forming part of Letters Patent No. 692,279, dated February 4, 1902.

Application filed February 23, 1900. Serial No. 6,227. (No model.)

To all whom it may concern:

Be it known that I, JOHN F. HAMILTON, a citizen of the United States, residing at South Framingham, in the county of Middlesex and 5 State of Massachusetts, have invented certain new and useful Improvements in Straw-Braid-Sewing Machines; and I do hereby declare the following to be a full, clear, and exact description of the invention, such as will 10 enable others skilled in the art to which it appertains to make and use the same.

The present invention relates to an improvement in straw-braid-sewing machines.

Heretofore it has been the practice in sewing straw-braid having a beaded or fancy edge to do the work by hand, and so far as I am aware no machine has heretofore been produced for successfully sewing such braid.

The object of the present invention is to re- 20 organize and improve the construction of straw-braid-sewing machines, so they may be used to sew beaded or fancy edged braids.

The present invention consists in the improvement in straw-braid-sewing machines 25 hereinafter described and claimed.

In the accompanying drawings, illustrating my invention, Figure 1 is a front elevation of part of the well-known Wilcox & Gibbs straw-braid-sewing machine. Fig. 2 is a sectional side elevation on the line $\alpha\alpha$ of Fig. 1 looking in the direction of the arrow, and Fig. 3 is a plan view of the presser-foot removed from the machine.

The presser-bar 1, the needle-bar 2, the 35 needle 3, the work-support 4, the looper 5, and the feed-surface 6 are or may be the same as shown in the patent to Wilcox, No. 218,413. The combined presser-foot and guide (indicated by the general reference-letter P) is se- 40 cured to the presser-bar 1 in the usual manner. The presser-foot 7 is similar in all re- 45 respects to the presser-foot of the said patent and operates in substantially the same man- 50 ner.

In Fig. 2 I have shown the braid B in the 55 position in the machine which it occupies while it is being sewed. This braid, it will be observed, has the beaded or fancy edge 8, the uniting rows of stitches being indicated 60 by 9. The braids 10 and 11 are in the position which they occupy while they are being sewed together—that is to say, the beaded

edge of the braid 10 lays closely against the presser-foot 7, and the flat part of the braid 11 is extended underneath the braid 10 and the 55 presser-foot 7, and the two braids are united by these seam of stitches being made. It is plain that if a guide of the form shown in the said patent to Wilcox were employed in sewing braid of this character the beaded or 60 fancy edges of the braid would be crushed or the braid would not be held firmly enough together to secure the proper action of the sewing mechanism. So, therefore, I have pro- 65 vided the guide 12 for the edge of the braid 11 and supported it from the presser-foot by means of an arch 13, which extends from the presser-foot upwardly and rearwardly over the beaded or fancy edge of the braid and down opposite the edge thereof. I have also 70 made the lower surface of the guide 12 higher than the bottom of the presser-foot 7. By this means under no circumstances will the downward pressure of the presser-bar press the guide down upon the material. This fea- 75 ture is of considerable importance, as it prevents the feed-surface from pressing the braid against the under side of the guide 12, which would operate to make it difficult if not im- 80 possible to sew around sharp curves. By the construction which I have adopted the work may be turned easily as it is going through the machine and properly presented to the needle.

I am aware of the patent to Wiseman, No. 85 285,333; but my invention is clearly to be dis- 85 tinguished therefrom and in the following im- 90 portant respects: First, in that machine the presser-foot is identical with the guide and presses the braid being fed into the machine 90 and not the braid which had been just pre- 95 viously feed into the machine; second, the lower side of the guide is much lower than the lower side of the tongue which engages the braid to which the new braid is being 95 sewed, and, third, the feed-surface is directly opposite the guide and presses the material against it and not against the tongue, which corresponds to the presser-foot in my device.

Having thus described my invention, I 100 claim as new and desire to secure by Letters Patent of the United States—

In a sewing-machine for sewing straw braid provided with a beaded edge, the combina-

tion with a feed-surface, of a presser-foot arranged to bear upon the surface of the upper braid at one side of the bead and to coöperate with the feed-surface to clamp the upper 5 and lower braids therebetween and feed the same, a guide for the edge of the upper braid arranged at a sufficient distance above the feed-surface to be out of contact with the lower braid and an arch spanning the space 10 between the presser-foot and the guide for

supporting the guide from the presser-foot extending over the bead of the upper braid and out of contact therewith, substantially as described.

In testimony whereof I affix my signature 15 in presence of two witnesses.

JOHN F. HAMILTON.
